ROTARY ABUTMENT PUMP OR MOTOR

Christopher G. Muller, Willcox, Ariz.

Application November 4, 1946, Serial No. 707,617

3 Claims. (Cl. 103—143)

1

My invention relates to fluid motors and pumps, and it has among its outstanding general objects to provide a device of the character indicated which is simple in construction, relatively inexpensive to manufacture, and highly efficient in practical use in that it incorporates no delicate parts likely to get out of order.

More specifically, it is an object of the invention to provide in a device of this kind novel valves and control means therefor for effecting in the case of a pump the drawing in and expulsion of fluid; or in the case of a motor the admission of and expulsion of a motive fluid.

Additionally and more specifically stated, the invention contemplates a device as indicated which involves twin rotors preferably spaced from one another within a casing, valves associated with each rotor, an interconnection between corresponding valves of the respective rotors, and means for controlling the valves preferably taking the form of a pin and groove arrangement associated with at least one set of valves and an adjacent casing portion.

Still another object of the invention is to provide in a pump or motor, means associated with its casing closure for controlling the operation of one or more rotor-carried valves.

A further object of the invention is to provide a fluid pump or motor including a casing-carried rib for spacing two fluid actuating (or actuated) rotors, said rib having a five-fold function in that it firstly seals fluid grooves in adjacent rotors; secondly, carries an operative connection between corresponding valves of the respective rotors; thirdly, provides a separating bearing for the respective rotors; fourthly, provides circumferentially spaced fluid inlets and outlets for fluid grooves; and, fifthly, carries laterally projecting fluid damming bosses received in the respective fluid grooves of adjacent rotors between the fluid inlets and outlets of same.

The foregoing and other objects and advantages of the invention will be readily apparent to those skilled in the art upon reference to the accompanying drawings which illustrate a preferred example of my inventive concept.

It is to be understood, however, that the invention is susceptible of any other mechanical expressions within the spirit and scope of the subject matter claimed hereinafter.

In the drawings, wherein the same reference characters have been used to designate the same parts throughout the several views,

Figure 1 is a perspective view of a pump or motor embodying my invention;

2

Figure 2 is a central cross-sectional view through the unit of Figure 1;

Figure 3 is a sectional view taken on the line 3—3 of Figure 2 and looking in the direction of the arrows:

Figure 4 is another sectional view taken on the line 4—4 of Figure 2;

Figure 5 is a view of one of the outer casing closure plates, it having been taken on the line 5—5 of Figure 2.

Referring to the drawings by reference characters, 10 is a base which is adapted to be bolted to a suitable support (not shown). The pump or motor comprehends the annular casing 11 which is open at each end and is provided with the medial inwardly extending circumferential rib 11a.

Rotatable in contact with the inner end of the circumferential casing rib 11a is the central medial disk 12 which is keyed, or otherwise made fast to, the concentric shaft 13. This shaft 13 is the power input shaft in the case of a pump and the power take-off shaft in the case of a motor, it being understood, as heretofore indicated, that the unit is adapted, without structural change, to be used as either a pump or a motor.

The shaft 13 as indicated in Fig. 2 extends through bushed concentrically located and aligned holes 14 in duplicate closure plates 15. These closure plates 15 take the form of annular disks and the shaft 13 is supported at opposite sides of the casing in bearings 15c which are received in cup-like members 15a. The endless marginal flanges of the cup members 15a are secured by means of machine screws 15b or the like to the outer surface of the closure plates 15 about the bushed openings 14 thereof. The bearing assemblies 15c are of the ball bearing race type and are standard. Hence, a detailed illustration of same has not been deemed necessary.

The closure plates 15 of the casing 11 are secured to the latter by means of machine screws or the like 16 as indicated in Figures 1 and 2.

In carrying out the invention I employ in the illustrated instance two fluid actuating (or, in the case of a motor, "actuated") disk form rotors 17 each of which is fast on the shaft 13 at opposite sides of the rotatable central disk 12. Each rotor 17 has a circular inner surface fluid-receiving groove 17b, as shown. The respective disk-form rotors 17 are adapted to substantially fully occupy and revolve in the spaces between closure plates 15 and the central "partition" 55 which is provided by the casing rib 11a and the

rotatable central disk 12. The closure plates 15 retain the respective shaft driving or rotor disks 17 in assembly.

As I have shown in Figures 2 and 3, each of the rotor disks 17 has diametrically opposite circular cut-outs 17a within which rotatably fit the disk valves 18. The valve-receiving cut-outs 17a of each rotor 17 are preferably, although not necessarily, aligned with one another.

Each of the disk valves 18 has an arcuate groove 18a in its inner surface indicated at 18a, and this groove 18a conforms in width, depth and curvature to the inner surface groove 17b of the related rotor disk 17. The function of this groove arrangement 17b, 18a will be understood as the description proceeds, it being noted that casing rib 11a contacts the rotors 17 to seal the fluid grooves 17b thereof.

Having reference now to Figures 2, 3 and 4 it will be noted particularly from an inspection of Figure 2 that the medial casing rib 11a has projecting laterally from each side a fluid damming boss 19. These fluid damming bosses 19 extend into the respective fluid-receiving rotor grooves 17b between the inlets and outlets 21a, 20a thereof—which latter also extend through rib 11a to the exterior of casing 11. Bosses 19 have a substantially fluid tight fit in grooves 17b.

Figures 3 and 4 illustrate the casing 11 as having an inlet passage 21 connecting through rib 11a with the rib-provided inlet passage 21a. Figures 3 and 4 also indicate the casing-provided fluid outlet passage 20 connecting with the rib-provided outlet passage 20a.

It will be understood from the foregoing and from inspection of the drawings that when either of the disks 18 approaches the related boss 19 of its groove 17b the disk is adapted to be turned so as to allow the boss to pass through the groove 18a of said disk to allow for the exhaust and admission of fluid, or vice versa, as the case may be, from the passages 20a, 21a.

To effect the above mentioned control of the valves, I preferably provide each adjacent closure plate 15 with a pair of radially spaced grooves 22 (as illustrated in Fig. 5). These grooves are adapted to receive the laterally projecting pins 23 extending from the disk valves 18 at opposite sides of their centers. Actuation of the valves to the groove aligning position, as shown (lower right) Fig. 3, is effected by the cam portions 22a of the closure plate grooves 22. As soon as a boss 19 has been passed by a valve 18, the closure grooves 22 coat with the valve-carried pins 23 to swing the valves 18 to the operative groove-closing position indicated at the upper left in Figure 3 so as to effect the pulling in of fluid in the case of a pump or drive of the rotors 17 by the fluid impinging against the valve 18 in the case of a motor.

Adjacent valves 18 of each of the rotor disks 17 (when they are aligned, as they preferably will be) are connected by the concentric pin 24, it being understood that related valves are keyed to said pin 24. The pin 24 extends through a sleeve 25 in the central shaft-carried disk 12 as best indicated in Figure 2. The operation of one valve 18, therefore, effects operation of the related valve 18 of the other rotor 17.

The use of two pins 23 for each of the valves 18 at opposite sides of the center thereof is desirable to obviate possibility of the valves jamming due to sticking of one pin 23 in its closure-provided groove 22. By providing the pin and

groove valve control 22, 23 in each of the closure plates 15, much greater smoothness in valve operation and less strain is achieved.

A power import or take-off pulley 26 is provided on the shaft 13 as indicated in Figure 1.

Having thus described my invention, what I claim as my invention is:

1. A rotary-type fluid pump or motor comprising, a substantially circular open-ended casing forming a cylindrical chamber and provided with an internal circumferentially-extending integral rib portion which projects into said chamber towards the axis thereof, closure plates detachably secured to the open ends of said casing, an axial shaft journalled in said plates, said rib portion being arranged to divide said chamber into a pair of separate rotor-receiving spaces, a central disk member disposed within the inner circumference of said rib portion and fastened to said shaft, separate rotor members disposed within each of said spaces and secured to said shaft and rotatable relative to said casing in close contact with said rib portion and with opposite sides of said central member, each of said rotor members being provided with an annular fluid-receiving groove therein and circular cut-out portions, said cut-out portions in each rotor member being diametrically-opposed, disk-like valve members rotatably disposed within said cut-out portions, fluid damming bosses extending laterally from opposite sides of said rib portion into said fluid-receiving grooves, said casing and rib portion being provided with a fluid inlet at one side of each of said bosses and a fluid outlet at the other side thereof, the faces of said valve members which are adjacent said bosses being provided with arcuate grooves which are adapted to intermittently coincide with said fluid-receiving grooves to permit passage of said bosses, and means for actuating said valve members so as to align the valve-grooves with said fluid-receiving grooves.

2. A rotary-type fluid pump or motor comprising, a substantially circular open-ended casing forming a cylindrical chamber and provided with an internal circumferentially-extending integral rib portion which projects into said chamber towards the axis thereof, closure plates detachably secured to the open ends of said casing, an axial shaft journalled in said plates, said rib portion being arranged to divide said chamber into a pair of separate rotor-receiving spaces, a central disk member disposed within the inner circumference of said rib portion and fastened to said shaft, separate rotor members disposed within each of said spaces and secured to said shaft and rotatable relative to said casing in close contact with said rib portion and with opposite sides of said central member, each of said rotor members being provided with an annular fluid-receiving groove therein and circular cut-out portions, said cut-out portions in each rotor member being diametrically-opposed, disk-like valve member rotatably disposed within said cut-out portions, fluid damming bosses extending laterally from opposite sides of said rib portion into said fluid-receiving grooves, said casing and rib portion being provided with a fluid inlet at one side of each of said bosses and a fluid outlet at the other side thereof, the faces of said valve members which are adjacent said bosses being provided with arcuate grooves which are adapted to intermittently coincide with said fluid-receiving grooves to permit passage of said bosses, and means for actuating said valve members so as

to align the valve-grooves with said fluid-receiving grooves, and means carried by said central member for operatively connecting corresponding valve members of the respective rotor members for simultaneous movement.

3. A rotary-type fluid pump or motor comprising, a substantially circular open-ended casing forming a cylindrical chamber and provided with an internal circumferentially-extending integral rib portion which projects into said chamber towards the axis thereof, closure plates detachably secured to the open ends of said casing, an axial shaft journaled in said plates, said rib portion being arranged to divide said chamber into a pair of separate rotor-receiving spaces, a central disk member disposed within the inner circumference of said rib portion and fastened to said shaft, separate rotor members disposed within each of said spaces and secured to said shaft and rotatable relative to said casing in close contact with said rib portion and with opposite sides of said central member, each of said rotor members being provided with an annular fluid-receiving groove therein and circular cut-out portions, said cut-out portions in each rotor member being diametrically-opposed, disk-like valve members rotatably dis-

posed within said cut-out portions, fluid damping bosses extending laterally from opposite sides of said rib portion into said fluid-receiving grooves, said casing and rib portion being provided with a fluid inlet at one side of each of said bosses and a fluid outlet at the other side thereof, the faces of said valve members which are adjacent said bosses being provided with arcuated grooves which are adapted to intermittently coincide with said fluid-receiving grooves to permit passage of said bosses, and means for actuating said valve members so as to align the valve-grooves with said fluid-receiving grooves, said valve-actuating means comprising interengaging pin and groove means carried by the inner faces of said closure plates and adjacent faces of said valve members.
